[57] CLAIM

The ornamental design for an interlocking wedding band, as shown and described.

DESCRIPTION

FIG. 1 is a perspective view of an interlocking wedding band showing my new design, an engagement ring being shown in broken lines in interlocking engagement therewith for illustrative purposes only;

FIG. 2 is a perspective view of the interlocking wedding band per se;

FIG. 3 is edge view thereof;

FIG. 4 is a front elevational view thereof;

FIG. 5 is a rear elevational view thereof; and

FIG. 6 is a sectional view taken on line 6—6 of FIG. 5.
